DESIGN FOR A BOOTEE

Louis J. Epstein, Jersey City, N. J.

Application May 3, 1938, Serial No. 76,939

Term of patent 3½ years

To all whom it may concern:

Be it known that I, Louis J. Epstein, a citizen of the United States of America, residing in Jersey City, county of Hudson, and State of New Jersey, have invented a new, original, and ornamental Design for a Bootee, of which the following is a specification, reference being had to the accompanying drawing, forming part thereof.

Fig. 1 is a plan view of a bootee showing my new design.

Fig. 2 is a side elevational view thereof.

I claim:

The ornamental design for a bootee substantially as shown.

LOUIS J. EPSTEIN.
